UNITED STATES PATENT OFFICE.

MAX ROCKSTROH, OF KLEIN-SEDLITZ, NEAR PIRNA, GERMANY.

DUPLEX INKING-GEAR FOR PLATEN PRINTING AND FOR DIE PRESSES.

No. 890,455.

Specification of Letters Patent.

Patented June 9, 1908.

Application filed September 11, 1907. Serial No. 392,328.

To all whom it may concern:

Be it known that I, MAX ROCKSTROH, director, subject of the Kingdom of Saxony, residing at Klein-Sedlitz, near Pirna, Villa 5 Lützow, Germany, have invented certain new and useful Improvements in Duplex Inking-Gears for Platen Printing and for Die Presses, of which the following is a specification.

The object of this invention is to enhance 10 the distribution of ink in platen printing presses to a degree so far not accomplished.

So-called duplex inking gears are already known in which the inking rollers distribute the ink during the downward motion of the 15 roller carriage and in which these rollers are replenished with ink prior to their upward motion. In such inking gears the one set of rollers, which during its downward motion served for inking the form and which in con- 20 sequence had lost ink, was replenished with ink while below the form, so that it could serve for inking the form during its return journey together with the two other inking rollers which as yet had not given up their 25 ink during their downward motion. The covering-power secured in this manner was nearly equivalent to that usually obtained from six inking rollers.

According to the present invention the 30 covering secured with one inking is made equivalent with that obtainable from eight inking rollers, *i. e.* with double the number of inking rollers actually used.

The general arrangement of a duplex inking 35 gear with four inking rollers, for example, is indicated in the accompanying drawing, the gear being represented above the form in Figure 1, in its downward passage over the form in Fig. 2, below the form in Fig. 3, and 40 in its upward passage over the form in Fig. 4.

The inking rollers *a*, or rather their bearings, are fitted with springs to the roller frame *d* in the known manner, by placing spiral springs around their bearing spindles *f*. 45 The jockey rollers *b* are likewise supported in a flexible manner in the roller frame *d* by placing springs around their bearing spindles *g*. Pivots *i* of the roller frame engage with slots *l* for suspending the bar *e* the latter having 50 slanting guide surfaces *s*,—corresponding in number with the jockey rollers *b*—at its outer edge, which serves for supporting the cross-bars *h* of the jockey rollers *g*. Fixed stops *o* and *p* are provided below the 55 form *n*; the ends of the elastically supported inking roller spindles *f* come in contact

with the first mentioned stop *o* when the roller frame travels in a downward direction, while the stop *p* serves for lifting the bar *e* thus causing the studs *g* of the jockey rollers, or rather their cross-bars *h* to slide down the slanting guide surfaces *s* of bar *e*.

The method of operating is as follows:—The inking rollers *a* are saturated with completely tempered ink from the upper inking apparatus as soon as the roller carriage has arrived in its highest position. Several 60 jockey rollers *b* rest upon each of the inking rollers and these therefore also become saturated with the finely tempered ink. Upon 65 the downward motion of the rollers, which next takes place, the form is inked by all of the inking rollers; the small jockey rollers *b*, however, retain an ink supply by remaining out of contact with the inking rollers they 70 being supported by the roller frame and in consequence are carried with it past the form. Below the form a portion of the inking rollers comes in contact with the high speed cylinders *c*, there located, and owing to 75 all of the jockey rollers *b* coming into contact with the rollers *a* a linking of the entire number of the inking rollers is effected.

In the present case, which serves as an example, the high rotary speed of the cylinders, mounted below the former is transmitted to four inking and to five jockey-rollers, so as to form an entirely complete inking gear comparable with that of the best high speed presses.

Twelve rollers simultaneously serve for spreading the ink which has been conveyed by the jockey rollers and that which is still retained by the inking rollers by being rotated at a high speed from the cylinders 95 mounted below the form; in this manner the inking rollers are completely re-inked. The inking rollers together with the jockey rollers now start on their return journey over the form, the jockey rollers not being lifted off, 100 but resting upon the inking rollers and rotating with them during the second inking of the form, thus serving additionally as distributors during the backward travel, a process of very great importance not only with 105 discontinuous toned plates, having inset-drawings, but also with other difficult printing forms.

The difference in comparison with other known arrangements, is that not only some, 110 but that all of the inking rollers are provided with jockey rollers, and that each of

the former has not only one, but at least two of the latter; by this means a largely amplified storage and a fine distribution of the ink is secured. This augmented storage of ink or rather, ink reservoir, is capable of providing not only two, but all of the inking rollers with a fresh supply of ink, and, by combination of the many jockey rollers below the form, also an independent and complete inking gear is produced, such as, in its pyramid-like arrangement, is not excelled by the best inking-gear of high speed presses. A further difference consists in this, namely, that the jockey rollers, contrary to previous practice, are used as distributors for the second inking; while they served, in still earlier practice, as distributors both for the first as well as the second inking, they are now used, according to the invention, for the double purpose, namely, to serve on the one hand as an ink storage, to pass over the form without doing work, and, to replenish all of the inking rollers when below the form, and on the other hand, to act as distributors during the return passage.

Having now particularly described and ascertained the nature of my said invention and in what manner the same is to be performed I declare that what I claim is:

30 1. A duplex inking gear for presses comprising a reciprocating inking roller carriage,

inking rollers journaled therein, a jockey roller associating with each of the inking rollers, carrier means for the jockey rollers, and means whereby on the downward movement of the carriage the inking rollers ink the form and the jockey rollers are moved out of engagement with the inking rollers and on the movement of the carriage in the opposite direction the inking rollers are caused to again ink the form and the jockey rollers are moved into engagement with the inking rollers.

2. A duplex inking gear for presses comprising a reciprocating inking roller carriage, 45 inking rollers carried thereby, a jockey roller associating with each of the inking rollers, a shiftable means for maintaining the jockey rollers out of contact with the inking rollers when the carriage moves in one direction, 50 and means for actuating said shifting means whereby the jockey rollers are brought into contact with the inking rollers when the carriage moves in the opposite direction.

In testimony whereof I have hereunto set 55 my hand in presence of two subscribing witnesses.

MAX ROCKSTROH.
